UNITED STATES PATENT OFFICE.

HANS MUNDING, OF INNSBRUCK, AUSTRIA-HUNGARY.

STIRRING AND FROTH-BEATING MACHINE FOR CONFECTIONERS.

SPECIFICATION forming part of Letters Patent No. 769,485, dated September 6, 1904.

Application filed December 28, 1903. Serial No. 186,825. (No model.)

To all whom it may concern:

Be it known that I, HANS MUNDING, a subject of the Emperor of Austria-Hungary, residing at Innsbruck, Austria-Hungary, have invented 5 certain new and useful Improvements in Stirring and Froth-Beating Machines for Confectioners, of which the following is a specification.

The subject of this invention is a stirring 10 and froth-beating machine for confectioners, with two froth-beaters driven by a single shaft.

This machine is sufficient to froth, on the 15 one hand, all the eggs and butter required in a confectionery establishment and, on the other, to beat all the frothed cream, and all this requires only one person or one motor. Hitherto it was only possible to work one beater by means of a complicated mechanism.

20 What is especially of importance with regard to this machine is that the plates and kettles used by confectioners may still be used, as the openings in the wooden table-slab can be made larger or smaller.

25 The accompanying drawing gives a plan view of the machine.

On a table-plate with four legs and two lateral supports, which carry the actuating mechanism on top of the plate, there are inserted 30 the kettles or plates side by side in recesses, so that there is a beating or stirring device for each of the plates. As these stirring devices are, however, actuated by one common communicator-shaft *a*, the pastry mass in the 35 different plates is worked simultaneously. The mass is worked by the tools generally used in the manufacture of pastry, which for this purpose are provided with a long stem *c*, passing through the stationary central ring *g* and 40 compelled by a ring *h*, essentially arranged at its upper end and describing a horizontal circle to rotate in the shape of the mantle of a double cone. The sticks or beaters are so ar-

ranged that when worn out they can be replaced by pushing back the ring *d*, which is 45 a very great advantage. The guiding-arms *e* are adjustable by means of screws *f* and allow of changing the speed as required and also of giving the beaters a larger or smaller circle to move in. If the mass is ready, the 50 locking device *g* of the guide is opened, the ring *h* made loose and drawn out of the screw *i*, and the kettles, beaters, and sticks taken out. On starting the machine the *modus operandi* is just the opposite. The ring *h* can also 55 be adjusted by a slide and serves to hold a beating apparatus.

Instead of the beaters there may be used sticks or holders carrying balls with joints, allowing them to roll over the bottoms of the 60 plates.

In order to be able to regulate the speed of the machine when driven by a motor, a regulating-brake may be arranged on the driving-shaft. 65

What I claim as my invention, and desire to secure by United States Letters Patent, is—

In a stirring and froth-beating machine for a simultaneous frothing of different masses for making confectionery the combination 70 with a horizontal driving-shaft *a* of several vertical shafts actuated by the said horizontal shaft, of several horizontal adjustable arms with rings *h*, adjusted by means of screws *i*, of horizontal stationary arms *e* with rings *g*, 75 adjustable on the table and of stirring and beating tools with long stems *c* passing through the said rings *g* and *h* and describing a double cone around the stationary ring *g*, substantially as and for the purpose set forth. 80

In testimony whereof I have signed this specification.

HANS MUNDING.

In presence of—

HERM. M. SCHELLING,
ABRAHAM SCHLESINGER.
